WARPING APPARATUS

Eugene R. Alderman, South Hadley, Mass.

Application April 9, 1934, Serial No. 719,695

7 Claims. (Cl. 28—32)

This invention relates to warping apparatus and more particularly to an improved creel and appurtenances thereof.

The object of the invention is to provide an apparatus for eliminating waste time in the warping operation. To this end I employ a reversible creel arranged to present either of its sides as a front side facing the warper and provided with means for guiding the ends from a yarn supply on the front side of said creel to the warper whereby during the beaming on operation, the rear side of the creel is accessible to an operator for replenishing the yarn supply for a subsequent beaming on operation.

The invention contemplates the use of a duplicate set of dismountable reeds for the warper (each set comprising the usual block reed and condensing reed) one set being in active function on the reed carriage of the warper for beaming on the yarns from the front side of the creel, the other set of reeds being temporarily removed from the reed carriage with remnant ends of previously beamed on yarns reeded therethrough and wound around the same for temporary stowage in a position out of the way of the operator and of the yarns being beamed on.

A stowing frame is provided for containing the idle reeds with the yarn remnants reeded therethrough and the reed carriage has a support to receive the stowing frame for convenient assembly with its reeds when the latter are dismounted from the reed carriage. The stowing frame with its reeds rolled up in the reeded yarns is hung above the spools at the rear of the creel where the operator is replacing and tying in new spools during the beaming on of yarns from the front of the creel.

In the drawings which show a preferred embodiment of my invention,

Fig. 1 is an end elevation of the creel frame and a rear end portion of the reed carriage;

Fig. 2 is a front elevation of said creel frame with the spools removed therefrom (the rear side being a replica of the front);

Fig. 3 is a side elevation of the reed carriage of a warping machine;

Figs. 4 and 5 are front and side views respectively, of the condensing reed assembled with its adapter;

Fig. 6 is a group view of the several parts of the reed stowing frame, together with said block reed, condensing reed and condensing reed adapter;

Fig. 7 is a front elevation of the reed stowing

frame assembled in holding relation with said reeds;

Fig. 8 is a sectional view along line 6—6 of Fig. 7;

Fig. 9 is a plan view at the front end of the reed carriage; and

Figs. 10, 11, 12, and 13 are diagrammatic views showing the progressive steps in stowing away the yarn remnants of a previously beamed on warp preparatory to reversing the creel and continuing the warping from the replenished side of the creel.

Referring more particularly to the drawings, the creel is preferably in the form of an A-shaped frame 1 as shown in Fig. 1 with casters 2 swiveled to the base thereof whereby it may be swung around in position to present either of its inclined sides as a front side facing the warper. Each of the inclined sides of said creel are exactly alike and are provided with the usual skewers 3 for receiving spools 4 of yarn. Although I have shown a flanged form of spool rotatably mounted on said skewers I wish the term spool as herein used be understood as any form of yarn supply element from which the yarn is adapted to be drawn off for the warping operation.

Fixed to the upper end of the creel frame, one for each side thereof and exactly similar in form is a guide bracket 5 having mounted thereon a guide rail 6 and a yarn separating reed 7. The guide rail 6 is preferably in the form of a glass rod for smoothly guiding the yarns thereover and the reed 7 preferably has glass dents 8 between which the yarns pass for being separated on their course to the warper. Also fixed to the top of the creel frame is a double ended hanger 9 having depending supporting portions 10 and 11 overhanging and above each of said creel frame sides. The supporting portions 10 and 11 each have hook elements 12, 13, 14, and 15 for a purpose to be later described. Angle brackets 16 and 17 are also formed in said hanger for a purpose later described.

As shown in Fig. 1 yarns are being guided from the spools at the front side of the creel over the guide rail 6 through separating reed 7 and down to a block reed 18 which is mounted at the rear of the reed carriage 19 of the warping machine. As shown in Fig. 3 this machine comprises the usual warping reel or mill 20, and reed carriage 19 having a mounting 21 for the condensing reed 22 and a mounting 23 for the block reed 18. As shown in Fig. 9 a transverse support 24 is provided on the reed carriage, said support prefer-

ably comprising two arms each of which is pivoted to the reed carriage and adapted to extend transversely thereof in line for supporting the reed stowing frame during the assembly of 5 the reeds therewith as hereafter described. When not in use said arms of the support 24 may be folded against the sides of the reed carriage as shown in dotted lines in Figs. 3 and 9.

The reed carriage 19 is also provided with other 10 appurtenances of the character common in such apparatus which need not be described. The block reed 18 and condensing reed 22 are dismountable from their respective mountings 23 and 21. These two reeds are what I term herein 15 as a set of reeds, and I have provided said set in duplicate for use in combination with this apparatus. One set of reeds is shown as mounted on the reed carriage in Fig. 3. The other set of reeds of exactly similar form is indicated as 20 being contained in its stowing frame and rolled up therewith in yarn remnants for temporary stowing on hooks 14 and 15 of the hanger portion 11. There is a similar stowage frame for 25 each set of reeds and the details of one of said frames are shown in Figs. 4, 5, and 6. The stowing frame preferably comprises two long bars 25 and 26 of equal length and adapted to be held together upon the interposed reeds by hooked springs 30 and 31. These bars have a length 30 approximately equal to the width of the creel frame or the sheet of yarns led therefrom and only the end portions of the bars are adapted to rest in the hooks 12, 13, 14, and 15 of the hangers 10 and 11. The upper bar 25 and the 35 lower bar 26 each has formed therein a long slot 27 for receiving the block reed 18 and a short slot or notch 28 to receive the condensing reed 22. Inasmuch as the condensing reed 22 is shorter in height than block reed 18 an adapter 29 40 is fitted to the same as shown in Figs. 4 and 5 so that when laid against the block reed the entire assembly may be clamped snugly between the upper and lower bars 25 and 26 and held together by the detachable springs 30 and 31. 45 The operation of the apparatus may be described as follows, referring more particularly to views 10, 11, 12, and 13. Assuming that the yarn supply on the front side of the creel is nearly depleted and requires replenishing the warper is stopped and the ends are cut and tied together 50 at a point between the condensing reed and the warper. The cut off yarn remnants extending back to the creel will be left reeded through the several reeds 22, 18, and 7. The adapter 29 is 55 fitted to the top of the condensing reed as shown in dotted lines (Fig. 3) and the block and condensing reeds are then dismounted from the reed carriage and are brought together in juxtaposition and assembled within the stowage frame 60 comprising rods 25, 26 and springs 30, 31. During this assembling operation the lower rod 26 is conveniently supported in the transverse arms 24 on the reed carriage as shown in dotted lines in Fig. 3 (see also Fig. 11). Thereupon the stowing frame and its embraced reeds are rolled up 65 in the yarn remnants which extend back to the creel as shown in Fig. 12 and are finally hung on the forward portion 10 of said hanger 9 as shown in Fig. 13. When the reeds are thus in 70 stowed position it is desirable to prevent the yarn ends extending therefrom down to the spools from slackening up. Therefore there is provided as shown on the rear side of the creel in Fig. 1, a felt covered clamp bar 32 coextensive in length 75 with the glass rail 6 and held yieldingly against

the same with the clamped yarns therebetween. An encircling rubber band or spring (not shown) will serve to hold the clamp bar 32 against the rail 6. There is a duplicate clamp bar for each side of the creel and the idle clamp bar 32' and idle stowage frame bars 25' and 26' may be supported in the bracket 16 of the hanger. It will be understood that during the beaming on operation which has just been completed from the yarns on the front side of the creel, full spools have 10 been mounted on the rear side of the creel and their ends have been tied into the yarn remnants which have been stowed in the reeds on the hanger portion 11. Therefore the creel is now in condition to be reversed and bring its former rear 15 side to the front whereby its previously stowed reeds in the hanger portion 11 are unrolled and mounted on the reed carriage for active function. The new yarn ends are then tied to the warper and the warping proceeds. 20

It will be observed that in the use of this apparatus when changing from one supply of spools to the other the necessity of re-reeding the yarn ends is avoided. It will also be observed that the operator in replacing depleted spools with 25 full spools and tying in the same is able to work at the rear side of the creel entirely away from yarns running to the warp and therefore can accomplish these operations while the warp is being beamed. Furthermore, after each beaming 30 on operation when the reeds and yarn remnants are being stowed away preparatory to a reversal of the creel, the warper may be operated for beaming off to its section beam in the usual manner. These several features of operation made 35 possible by the use of my apparatus all contribute to a considerable saving of time and cost of labor in the warping.

It will be understood that the embodiment of the invention as shown and described is for purposes of illustration only and that the invention includes all modifications and equivalents which may fall within the scope of the appended claims. 40

I claim:

1. In warping apparatus of the type comprising 45 a creel, a warper and reed carriage having mountings thereon to receive the block reed and condensing reed, the combination with a duplicate set of reeds each set comprising a block reed and a condensing reed and either set adapted to be mounted on said reed carriage for guiding yarns from the creel to the warper, of a creel comprising a reversible frame adapted to present either of its two sides to the warper as its front side, each side of said creel frame being provided with means to receive spools of yarn, the yarns from one side being reeded through one set of reeds and the yarns from the other side being reeded through the other set of reeds, a hanger support at each side of said creel 60 for stowing a set of reeds above the spools and duplicate guiding means at the upper end of each side of said creel frame for alternatively serving to guide the yarns from the spools at the front of said creel to the set of reeds on said 65 reed carriage and to guide the yarns from the spools at the rear of said creel to the set of reeds stowed on said hanger support. 70

2. In warping apparatus of the type comprising 75 a creel, a warper and reed carriage having mountings thereon to receive the block reed and condensing reed, the combination with a duplicate set of reeds each set comprising a block reed and a condensing reed and either set adapted to be mounted on said reed carriage for guid- 75

ing yarns from the creel to the warper of a creel comprising a reversible A-shaped frame adapted to present either of its two inclined sides to the warper as its front side, each side of said 5 creel frame being provided with means to receive spools of yarn, the yarns from one side being reeded through one set of reeds and the yarns from the other side being reeded through the other set of reeds, a double ended hanger 10 mounted at the top of said creel frame having supporting portions overhanging each side of said frame for stowing a set of reeds above the spools and duplicate guiding means at the upper end of each side of said creel frame for alter- 15 natively serving to guide the yarns from the spools at the front of said creel to the set of reeds on said reed carriage and to guide the yarns from the spools at the rear of said creel to the set of reeds stowed on said hanger sup- 20 port.

3. In warping apparatus of the type comprising a creel, a warper and reed carriage having mountings thereon to receive the block reed and condensing reed, the combination with a duplicate set of reeds each set comprising a block 25 reed and a condensing reed and either set adapted to be mounted on said reed carriage for guiding yarns from the creel to the warper, of a creel comprising a reversible frame adapted to 30 present either of its two sides to the warper at its front side, each side of said creel frame being provided with means to receive spools of yarn, the yarns from one side being reeded through one set of reeds and the yarns from the 35 other side being reeded through the other set of reeds, a hanger support at each side of said creel for stowing a set of reeds above the spools and duplicate guiding means at the upper end of each side of said creel frame comprising a 40 guide rail and a separating reed for alternatively serving to guide the yarns from the spools at the front of said creel to the set of reeds on said reed carriage and to guide the yarns from the spools at the rear of said creel to the set of 45 reeds stowed on said hanger support.

4. In warping apparatus of the type comprising a creel, a warper and reed carriage having mountings thereon to receive the block reed and condensing reed, the combination with a duplicate set of reeds each set comprising a block 50 reed and a condensing reed and either set adapted to be mounted on said reed carriage for guiding yarns from the creel to the warper, of a creel comprising a reversible frame adapted to present either of its two sides to the warper as its front side, each side of said creel frame being provided with means to receive spools of yarn, the yarns from one side being reeded through one set of reeds and the yarns from the other side being reeded through the other 55 set of reeds, a double ended hanger mounted at the top of said creel frame having supporting portions overhanging each side of said frame for stowing a set of reeds above the spools, duplicate guiding means at the upper end of each side 60 of said creel frame comprising a guide rail and a separating reed for alternatively serving to guide the yarns from the spools at the front of said creel to the set of reeds on said reed carriage and to guide the yarns from the spools at the rear of said creel to the set of reeds stowed on said hanger support and a reed stowing frame comprising a pair of bars long enough to extend across the width of said creel frame and adapted to be hung on said hanger support, said frame being arranged to hold a set of reeds 65 in juxtaposition and to have the yarn lengths 70

from the creel to the warper wound around the same when stowed on said hanger support.

5. In warping apparatus of the type comprising a creel, a warper and reed carriage having mountings thereon to receive the block reed and condensing reed, the combination with a duplicate set of reeds each set comprising a block reed and a condensing reed and either set adapted to be mounted on said reed carriage for guiding yarns from the creel to the warper, of a creel comprising 10 a reversible A-shaped frame adapted to present either of its two inclined sides to the warper as its front side, each side of said creel frame being provided with means to receive spools of yarn, the yarns from one side being reeded through 15 one set of reeds and the yarns from the other side being reeded through the other set of reeds, a double ended hanger mounted at the top of said creel frame having supporting portions overhanging each side of said frame for stowing a 20 set of reeds above the spools, duplicate guiding means at the upper end of each side of said creel frame for alternatively serving to guide the yarns from the spools at the front of said creel to the set of reeds on said reed carriage and to guide the 25 yarns from the spools at the rear of said creel to the set of reeds stowed on said hanger support and a reed stowing frame comprising a pair of bars long enough to extend across the width of said creel frame and adapted to be hung on said 30 hanger support, said frame being arranged to hold a set of reeds in juxtaposition and to have the yarn lengths from the creel to the warper wound around the same when stowed on said hanger support. 35

6. In a warping apparatus of the type comprising a creel, a warper and reed carriage having mountings thereon to receive the block reed and condensing reed, the combination with a duplicate set of reeds each set comprising a block 40 reed and a condensing reed and either set adapted to be mounted on said reed carriage for guiding yarns from the creel to the warper, of a creel comprising a reversible A-shaped frame adapted to present either of its two inclined sides to the 45 warper as its front side, each side of said creel frame being provided with means to receive spools of yarn, the yarns from one side being reeded through one set of reeds and the yarns from the other side being reeded through the other 50 set of reeds, a double ended hanger mounted at the top of said creel frame having supporting portions overhanging each side of said frame for stowing a set of reeds above the spools, duplicate guiding means at the upper end of each side 55 of said creel frame comprising a guide rail and a separating reed for alternatively serving to guide the yarns from the spools at the front of said creel to the set of reeds on said reed carriage and to guide the yarns from the spools at the rear of said creel to the set of reeds stowed on said hanger support and a reed stowing frame comprising a pair of bars long enough to extend across the width of said creel frame and adapted to be hung on said hanger support, said frame being 60 arranged to hold a set of reeds in juxtaposition and to have the yarn lengths from the creel to the warper wound around the same when stowed on said hanger support. 65

7. In apparatus of the class described, the combination with a warper having a dismountable set of reeds in duplicate, of a creel comprising a reversible frame adapted to present either of its sides as a front side facing the warper, each side of said creel provided with means to receive a plu- 75

rality of spools of yarn, yarn guiding means mounted on each side of said creel above said spools, each of said yarn guiding means comprising a guide rail and a yarn separating reed spaced 5 therefrom, said separating reed being located on the outer side of said guide rail with respect to the adjacent side of said creel whereby the yarns are guided to said warper from the spools on the front side of said creel for the beaming on operation, and a double ended hanger mounted at the

top of said creel frame having supporting portions overhanging each side of said creel, one of said supporting portions being at the back of said creel during the beaming on operation and arranged to receive in stowed position thereon an idle set of reeds dismounted from said warper with the yarns from the back of said creel reeded therethrough.
